UNITED STATES PATENT OFFICE.

BLUFORD W. BROCKETT AND ALBERT L. LORD, OF CLEVELAND, OHIO, ASSIGNEES, BY
MESNE ASSIGNMENTS, TO THE FIRST TRUST & SAVINGS COMPANY, OF CLEVELAND,
OHIO, A CORPORATION OF OHIO, TRUSTEE.

IRONING-MACHINE.

1,329,502.

Specification of Letters Patent. Patented Feb. 3, 1920.

Application filed May 26, 1914, Serial No. 841,117. Renewed July 15, 1918. Serial No. 245,070.

To all whom it may concern:

Be it known that we, BLUFORD W. BROCKETT and ALBERT L. LORD, citizens of the United States, residing at Cleveland, in 5 the county of Cuyahoga and State of Ohio, have invented certain new and useful Improvements in Ironing-Machines, of which the following is a specification.

This invention relates generally to improvements in ironing machines, and particularly to bosom presses.

More specifically the invention relates to a bosom press comprising a frame, an ironing board mounted thereon, a suitable chest 15 supporting bracket carried by the frame, a chest support mounted in said bracket, an ironing chest slidably mounted in said chest support and having a neck band recess, a neck band former mounted upon the ironing board and having a forward portion adjustable along the board for various sizes of neck bands, and suitable means arranged 20 between the neck band former and the ironing chest for adjusting the position of the latter with respect to the movable portion 25 of the neck band former, and comprising a cam carried by the forward movable portion of the neck band former engaging a friction roller carried by the chest and thereby moving the chest so that the front 30 edge of the neck band recess therein will just clear the forward edge of the movable portion of the neck band former, the chest when in elevated position normally assuming a 35 position by gravity such that the roller carried by the chest will always engage the cam member carried by the neck band former irrespective of its adjustment.

The invention may be further briefly summarized as consisting in the construction and combination of parts hereinafter set forth in the following description, drawings and claims.

Referring to the drawings, Figure 1 is a 45 side elevation of a portion of a machine constructed according to my invention; Fig. 2 is a top plan view of the ironing chest and some of the parts below with parts broken away and in section, the section line being 50 taken horizontally through one of the slots in the chest support and then continued as a section through the parts which receive the pipes; Fig. 3 is an enlarged view of a portion of the ironing board showing the

neck band former; Fig. 4 is a sectional view 55 through these parts showing the cam member and the rear portion of the ironing chest; and Fig. 5 is a detailed end elevation of the upper portion of the machine, as seen from the left in Fig. 1. 60

In carrying out the invention any preferred form and construction of parts may be employed, so long as they possess the necessary characteristics, but I have shown one arrangement which is effective in operation, 65 and in such embodiment 1 represents a frame having an upwardly extending member 2 for supporting the ironing board 3. The frame is also provided with suitable bearings 4 supporting a shaft 5 provided 70 with a main operating gear wheel 6 adapted to be driven from any suitable mechanism, not shown and not forming a part of the invention. The frame is also provided at the rear of the shaft 5 with a supporting 75 bracket 7 having a socket or bearing 8 open at the top and for a purpose to be described.

Pivoted to the lower part of the frame or mounted in any suitable manner, not shown and common to this type of machine, is a 80 bar or lever 9 connected by a link 10 with a crank pin 11, and extending from the side of the gear wheel 6. There is one of these levers and links on each side of the machine and they are connected at the top by a suitable cross bolt 12 and by a shaft 13 for a purpose to be described. All of this mechanism is of a general nature, and hence needs 85 no further specific description.

Extending upward from the head end of 90 the ironing board is a projection 14 shown in Fig. 4, having a transverse recess 15 for receiving a strip 16 secured to a neck band base plate 17. This plate carries a longitudinally disposed guide 18 fitting into a 95 guideway 19 of a movable neck band member 20, which is curved at its forward end to conform to the general configuration of a neck band. This neck band member 20 is provided with obliquely disposed guideways 100 21 adapted to receive slidable bars 22 each of which carries at its rear end a foot portion 23 fitting in the rear back corners of the neck band member 20 and to finish the general heart-shaped construction of this 105 member, as shown, as is usual in devices of this sort. Mounted in a suitable recess in the neck band member 20 is a pair of mesh-

ing gears 24 and 25 which in turn mesh with suitable teeth 26 arranged on the bars 22. It will be seen from this gearing that upon a movement of one of the bars the other one 5 will be moved in a similar manner. Mounted in the neck band member 20 and to one side of the bars is an operating pinion 27 meshing with teeth on the bar having a thumb piece 28 extending above the upper 10 cover member 29 of the movable portion of the neck band former. Secured to the gear 25 is a ratchet wheel 30 which coöperates with a latch 31 shown in dotted lines in Fig. 3 and having an operating handle 32 arranged above the cover 29. By the arrangements of the parts it will be seen that upon the operation of the finger piece 28 there will be a relative movement between the bars 22 and the forward movable portion 15 of the neck band former.

Extending from each of the foot portions is a pin 33 engaging in a transverse recess 34 in the upper face of the projection 14. By this arrangement it will be seen that the 20 foot portions as well as the bars 22 will be held against movement along the face of the board and when the pinion 27 is operated the forward portion of the neck band former will move along the board. In this 25 way the neck band former is adjusted to various sizes of neck bands.

Extending upward from the upper surface of the cover plate 29 is a cam member 35 having a curved front cam edge 36, as shown in 30 Figs. 1 and 4, and this cam face coöperates with a friction roller 37 mounted between ears 38 rigid with and preferably forming a part of a longitudinally movable ironing chest 39. The ears 38 are mounted upon 35 the innermost portion of the curved wall of the neck band recess 40 which is formed in the head end of the ironing chest. This chest has lateral extensions 41 extending to the side of the machine, as shown in Fig. 2, and 40 each is connected to a suitable pipe 42. This pipe telescopes into a suitable stuffing box 43 forming a part of a steam connection 44 which receives steam from any suitable source. This connection has a shank 45 for 45 a purpose to be described.

Mounted in the socket or bearing 8 is a short shaft 46 which is extended beyond the ends of this bearing and is bored out to receive the shanks 45. Between the connections 44 and the ends of the bearing 8 are bearings 47 integral with arms 48 which in turn are formed integral with an ironing chest support 49 extending over a portion of the ironing chest and provided at 50 its side edges with downwardly extending flanges 50 each of which is provided with a pair of slots 51, one toward the front and one toward the rear, and each of these slots receives a suitable bolt 52 threaded into the 55 ironing chest. The lateral extensions 41

pass under these flanges. This support is provided with upwardly extending bearing portions or ears 53, shown in Figs. 1 and 5, and these ears receive a shaft 54 pivotally connected to a link member 55. This link member receives the end of a rod 56 secured in another link member 57 pivotally mounted upon the shaft 13.

The arrangement of the parts is such that when the levers 9 are thrown to the rear, as 75 shown in dotted lines in Fig. 1, the ironing chest structure is drawn into vertical position and moves downward by gravity until the bolts 52 engage the lower ends of the slots 51, as shown. When the shirt is applied and the 80 neck band former has been adjusted in the manner described, which means that the forward portion has been moved forward or backward along the board until the neck band is stretched, then the power is transmitted to the machine in a manner such that the chest is swung over upon the board. In accomplishing this result, however, the roller 37 engages the edge face 36 of the 85 cam member 35 and the ironing chest automatically adjusts itself to the board, so that the edge of the neck band recess 40 therein misses the forward edge of the movable portion of the neck band former. When the ironing member is raised and there is an 90 inclination given to the support 49 the ironing chest gradually moves backward and the roller 37 follows the edge of the cam until the bolts 52 rest in the ends of the slots.

Having described our invention, we 100 claim:

1. In an ironing press, an ironing board, a neckband former thereon, means for adjusting the neckband former to various sizes of neckbands, an ironing chest having 105 a neckband recess, means whereby adjustment of the neckband former effects proper ironing relation of the chest and neckband former, and means for producing relative movement of the ironing chest and board. 110

2. In an ironing press, an ironing board, a neckband former thereon having a movable portion and a fixed portion, a movable ironing chest having a neckband recess, means whereby adjustment of the movable portion of the neckband former effects adjustment of the chest to properly position the neckband recess with respect to the neckband former, and means for producing relative movement of the ironing board and 115 chest.

3. In an ironing press, an ironing board, a neck band former thereon having a movable portion and a fixed portion, a movable ironing chest having a neck band former 125 recess, suitable mechanism arranged between the movable portion of the neck band former and the chest for bringing about the adjustment of the recess in the chest to the neck band former on the ironing board, 130

and means for bringing about a relative movement of the ironing board and ironing chest.

adjusting said form and said moving mechanism whereby adjustment of the forward portion of the form maintains proper registry of the form and the recess in the board. 65

4. In an ironing press, an ironing board, a neck band former thereon having a movable portion and a fixed portion, a movable ironing chest having a neck band former recess, a cam member carried by the movable portion of the neck band former and engaging the chest for adjusting it to properly position the neck band recess therein with respect to the neck band former, and means for bringing about a relative movement of the ironing board and ironing chest.
- 5 a neck band former thereon having a movable portion and a fixed portion, a movable ironing chest having a neck band former recess, a cam member carried by the movable portion of the neck band former and engaging the chest for adjusting it to properly position the neck band recess therein with respect to the neck band former, and means for bringing about a relative movement of the ironing board and ironing chest.
- 10

9. In a machine for ironing shirt bosoms, the combination with a board for supporting a shirt, of a neckband support mounted upon said board and having an adjustable forward portion, an ironing member having a recess therein to receive said neckband support, mechanism for relatively moving said board and said member into co-operative pressing relation with the forward portion of the neckband support registering with the recess in said member, and means for simultaneously adjusting said neckband support and said mechanism to maintain registration of the forward portion of said neckband support with said recess in any adjustment of said support. 70 75 80

15 5. In an ironing press, an ironing board, a neck band former mounted thereon and having a movable portion and a fixed portion, a movable ironing chest having a neck band former recess, a cam arranged upon
20 the movable portion of the neck band former, a friction roller carried by the chest adapted to engage said cam and cause the positioning of the recess in the chest with respect to the neck band former, and means
25 for bringing about a relative movement of the ironing board and ironing chest.

10. In a machine of the character described, the combination with a board for supporting an article to be operated upon by the machine, of a form projecting from the surface of said board having an adjustable forward portion, a member adapted to press the article supported on the surface of said board and having a recess therein to receive said form, mechanism for relatively moving said board and member into co-operative pressing relation with the forward portion of the form registering with the recess in said member, means for adjusting said form, and means whereby the adjustment of the forward portion of said form sets the machine to maintain proper registration of the form and recess in any adjusted position of the form. 100

6. In a machine of the character described, the combination with a board for supporting an article to be operated upon by the machine, of an adjustable form projecting from the surface of said board, a member adapted to engage the article supported on the surface of said board and having a recess therein to receive said form, mechanism 30 for relatively moving said board and member into co-operative relation, and means for simultaneously adjusting said form and said mechanism to register said form with the recess in said member.

40 7. In a machine for ironing shirt bosoms, the combination with a board for supporting a shirt, of an adjustable neck band support mounted upon said board, an ironing member having a recess therein to receive said
45 neck band support, mechanism for relatively moving said board and said member into co-operative relation, and means for simultaneously adjusting said neck band support and said mechanism to register said neck band
50 support with said recess.

8. In a machine of the character described, the combination with a board for supporting an article to be operated upon by the machine, of a form projecting from the surface 55 of said board and having an adjustable forward portion, a member adapted to press the article supported on the surface of said board and having a recess therein to receive said form, mechanism for relatively moving 60 said board and member into co-operative pressing relation with the forward portion of the form registering with the recess in said member, and means for simultaneously

11. In a machine of the character described, the combination with a board for supporting an article to be operated upon by the machine, of a form projecting from the surface of said board having an adjustable forward portion, a member adapted to press the article supported on the surface of said board and having a recess therein to receive said form, mechanism for relatively moving said board and member into co-operative pressing relation with the forward portion of the form registering with the recess in said member, means for adjusting said form, and means whereby the adjustment of the forward portion of said form simultaneously sets the machine to maintain proper registration of the form and recess in any adjusted position of the form. 105 110 115
